UNITED STATES PATENT OFFICE.

KARL F. KEELER, OF PROVO, UTAH, ASSIGNOR TO KEELER AUTOMATIC HEADGATE COMPANY, OF PROVO, UTAH, A CORPORATION OF UTAH.

AUTOMATIC HEAD-GATE.

1,216,698.

Specification of Letters Patent. Patented Feb. 20, 1917.

Application filed April 5, 1916. Serial No. 89,012.

To all whom it may concern:

Be it known that I, KARL F. KEELER, a citizen of the United States, residing at Provo, in the county of Utah and State of Utah, have invented a certain new and useful Improvement in Automatic Head-Gates, of which the following is a specification.

My invention relates to automatic head-gates for controlling the flow of liquid into a delivery duct or conduit. My invention is useful, for example, in irrigating projects for controlling the amount of water flowing from the supply ditch or canal into the lateral from which the water is to be distributed. My device is related in a general way to the devices shown in my prior Patents No. 1,138,485 issued May 4th, 1915, and No. 1,147,948 issued July 27th, 1915. It is also related, in a general way, to my co-pending application filed on the 22nd day of January, 1916, Serial No. 73539.

In my prior devices the gate proper and the water box which operates it are shown to be suspended from two separate suspending elements located at either side of the gate. This required special means for preventing lateral movement of the gate and attached parts. The object of my present invention is to provide a practical means for suspending the parts from a single element located approximately in line with the center of gravity. This simplifies the structure and dispenses with much of the mechanism previously employed for guiding the parts in their vertical movement. Ancillary to this object, it is my purpose to provide a supporting spring of special design whereby the increase in weight of the water box will increase the amount of spring in contact with its support thereby stiffening the spring as the box descends.

It is also my object to provide a simplified construction of headgate box and parts inclosing the same. It is also one of my objects to provide novel means for preventing the collection of sediment in the headgate box. In my present construction I make the box approximately cylindrical and let the source water into it from one side (that is, off center). This produces a whirl or vortex. I form a small hole near the center of the bottom and the waters flowing finally down through it sluice away any sand which might tend to collect.

Other contributory objects will become apparent as the description proceeds.

I accomplish my objects by the mechanism illustrated in the accompanying drawings, in which—

Figure 1 is a perspective (with portions broken away) showing apparatus embodying my invention.

Fig. 2 is a top plan view of the parts shown in Fig. 1.

Fig. 3 is an elevation of the parts shown in Fig. 2, most of the parts being shown in longitudinal section.

Fig. 4 is a perspective of the supporting spring.

Similar numerals refer to similar parts throughout the several views.

In the form selected to illustrate the invention, the major portion of the apparatus is formed of sheet metal. According to the design selected, the water is led to the apparatus through the supply conduit 1 and is led from it by the delivery conduit 2. At the junction of these two rises the casing 3, which is preferably cylindrical in cross section. Extending across the casing, near the front, is a front sheet 4 which extends down from a point near the top, to a point far enough above the floor of the conduit to avoid reducing the available cross sectional area thereof. This leaves an opening 5 between the lower edge of the front sheet and the floor of the conduit which may be regarded as the outlet port from the source.

As the casing is cylindrical, and the front sheet is flat, and located a short distance behind the foremost point of the casing, it leaves a space 6 in front of the front sheet. This is segmental in cross section and forms a well in which the water may rise to the level of the water in the source. Consequently, my device may be located at a distance from the source and the supply duct 1 may be of comparatively small cross section and yet the device will not be deprived of the influence of the changes of level in the source.

The width of the outlet port 5 is controlled, preferably, by a shut-off valve 7 which consists, in the present design, of a sheet metal plate guided in horizontal grooves 8. When the valve is shut the flow is entirely shut off from the delivery conduit 2. When the gate is open, it slides into

a housing 9 which extends laterally for receiving and guiding the shut-off valve. Said shut-off valve is, in the present design, operated by means of a rack 10 which meshes 5 with a pinion 11 fastened at the lower end of a rod 12. The upper end of this rod has a hand wheel 13 by which it is rotated.

The headgate consists of a sheet 15 of metal mounted so as to slide vertically just 10 behind the front sheet 4. It is guided vertically by two antifriction rollers 16 located at either edge and mounted upon studs 17 supported in the casing 3. The arrangement of the parts is perhaps best shown in 15 Fig. 2. Attached to and forming part of the headgate is a box or receptacle 20 which is approximately cylindrical, especially at the back. This receives water through the front opening 21 in the headgate 15, as best 20 shown in Fig. 1. Screen 22 is desirable to prevent floating objects from entering the box. It will be noted that the opening 21 is located off center—in the present instance being at the left of the center when viewed 25 as in Fig. 1. The object of this is two-fold. First, it will not be affected by the shut-off valve 7 until the latter is nearly closed; and second, it admits water in a stream entering from one side of the box. Consequently, the 30 flow tends to create a whirl or vortex in the box and prevents the deposition of sediment. A hole 23 is formed in the bottom of the box approximately at the center and this permits the escape of the sand laden water, and 35 hence the combined result is to keep the box clean and free.

The headgate and its attached water box are suspended upon a spring 26 which seats 40 upon a stationary bracket or shelf 27 fastened horizontally and centrally in the casing 3. The spring is in the form of a pyramidal spiral and at the upper end supports a rod 28 which passes down through a hole 29 in the bracket 27 and attaches to 45 a cross brace 30 fastened to the top of the water box. The parts are so arranged that the rod 28 will be in line with the center of gravity of the parts suspended thereon, the result being that the need of guiding means 50 to prevent sidewise motion of the headgate and water box is practically eliminated. In other words, the parts are suspended from the center and even without any extraneous guiding means there would be little, if any, 55 tendency of the parts to stick as they move up and down under the variations of load. By preference the guide rollers 16 are set obliquely and run in a channel 32 formed where the gate sheet 15 projects beyond the 60 sides of the water box 20. The result is that these rollers prevent the box and gate from rotating about the central vertical axis of the box. They also prevent the horizontal pressure of the water in the space 6 from 65 pushing the box backward against the back

of the casing. Furthermore, said rollers do not allow the box to move crosswise, thus preventing the vertical edges of the gate sheet 15 from rubbing on the casing 3.

Broadly considered, the action of my 70 present device is analogous to the action of the headgates shown in my prior patents. As the level of water in the source varies, it will vary the amount of water in the water box and hence will vary the weight imposed 75 upon the suspending mechanism. This will automatically raise or lower the headgate, and consequently increase or decrease the area of the outlet port 5, thus regulating the quantity of water passing through outlet port 5 in accordance with the desired 80 regulation, for example, a constant discharge.

In the present form, in which the water box and headgate are suspended upon a pyramidal coiled spring, the base of the spring 85 rests upon the supporting bracket 27. As the weight in the box increases, the amount of spring in contact with its support will increase. This is due to the fact that the 90 lower turns of the spring are of greater diameter than the upper turns and hence there is a greater leverage toward the bottom of the spring. The spring differs, therefore, from a truly helical spring where, under normal circumstances, the movement of 95 each turn would be uniform. As the amount of spring in contact with the shelf increases it has the effect of shortening the movable portion of the spring and hence has an effect 100 equivalent to stiffening the spring. Consequently, uniform increments of weight do not, in my construction, produce uniform increments of downward movement of the box and headgate. This makes it possible 105 for the device to operate in harmony or so closely in harmony with the laws of hydraulics as to render the device accurate for all practical purposes.

It will be understood that it is desirable to 110 construct the metallic parts of non-corrosive sheet metal. As there are, practically speaking, no bearings or hinged joints, there is practically nothing to get out of order and inspection will be required at very infrequent intervals.

Having thus described my invention what I claim as new and desire to secure by Letters Patent, is:

1. In a headgate, the combination of a 120 water box having a headgate attached thereto, and suspending means supported at a single point and attached to said box approximately in line with the center of gravity thereof.

2. In a headgate, the combination of a 125 water box having a headgate attached thereto and provided with a receiving opening at the side, a stationary support, a single spring mounted upon said support, and sus- 130

pending means connected at one end to said spring and at the other end to said water box, approximately in alinement with the center of gravity of the latter.

5. 3. In combination, a fluid conduit, a casing rising therefrom, a water box vertically movable in said casing, said box having a headgate attached thereto and a receiving opening in the side, and a coiled spring having its axis approximately in alinement with the center of gravity of said water box and its attached headgate, one end of said spring being fastened to said casing, and connections between the water box and the opposite end of the spring.

10. 4. In a headgate, a stationary support, a single spiral spring seated upon said support, and a headgate suspended from said spring, the point of attachment of the gate to the spring being in alinement, vertically with the center of gravity of the gate.

20. 5. In combination, a conduit having a casing rising therefrom, a water box vertically movable in said casing, said box having a headgate attached thereto and a receiving opening in the side, a single spring seated upon said casing, said spring being in the form of a pyramidal spiral with its larger end fastened to said casing, and a connecting rod attached to the smaller end of the spring and attached to the water box, said rod being coincident with a vertical line fastened to the center of gravity of the water box and its attached headgate.

35. 6. In combination, a conduit having a casing rising therefrom, a water box vertically movable in said casing, said box having a headgate attached thereto and a receiving opening in the side, a pyramidal coiled spring seated at its lower end upon said casing, a rod fastened to the upper end of said spring and fastened to said water box, and means for guiding the moving parts in a vertical direction.

45. 7. A device of the class described comprising a conduit having a casing rising therefrom, a bracket extending across said casing near the top, a water box vertically movable in said casing, said box having a headgate attached thereto and a receiving opening in the side and said bracket having an aperture directly over the center of gravity of the headgate, a single coiled spring attached to said bracket concentric with said aperture, and a rod fastened at one end to said spring and at the other end to the water box, said rod passing through the aperture in the bracket.

60. 8. A device of the class described, comprising a conduit having a casing rising therefrom, an approximately cylindrical water box in said casing, said water box having a headgate attached thereto and a receiving opening in the side, suspending means for said box, said suspending means

being substantially coaxial with the vertical axis of the box and being confined at one point substantially to the line of the central vertical axis of the box and therefore being substantially without effect to prevent the 70 rotation of said box about its vertical axis, and means for preventing said box from rotating about its vertical axis.

9. A device of the class described, comprising a conduit having a substantially cylindrical casing rising therefrom, an approximately cylindrical water box in said casing, said water box having a headgate attached to it and a receiving opening in the side, suspending means for said box, said 75 suspending means being substantially coaxial with the central axis of the box and confined at one point substantially to the line of the central axis of the box and therefore being substantially unable to prevent 80 the rotation of the box about its vertical axis, and anti-friction rollers interposed between the sides of the casing and the sides of the box for preventing the box from rotating about its central vertical axis.

25. 10. A device of the class described having a conduit provided with a substantially cylindrical casing surmounting it, a front sheet extending across said casing near the front of it and arranged vertically, a water 90 box having a receiving opening in the side and a headgate parallel and adjacent to said front sheet, a pyramidal spiral spring seated at its lower end upon said casing and having its central axis coincident with a 100 line passing vertically through the center of gravity of the water box, a rod fastened to the upper smaller end of said spring, the lower end of said rod being fastened to said water box for suspending it.

30. 11. In a device of the class described, a conduit surmounted by a substantially cylindrical casing, an upright front sheet extending across said casing near the front, a water box in said casing, said water box 105 having a headgate attached thereto parallel and adjacent to said front sheet, said water box being suspended at a single point approximately in line vertically with the center of gravity of said water box, whereby said water box would be capable of rotating about its own central axis, said headgate having a receiving opening near one side whereby the water entering would have a tendency to rotate said water box about its 110 central axis, and means for preventing rotation of said water box about its central axis.

35. 12. In a device of the class described, a vertically movable water box having a headgate attached thereto, said water box being approximately cylindrical in cross section and having an aperture near the center of its bottom, said headgate having a receiving opening located to one side of the center 120 130

whereby the water entering said opening tends to create a whirl in the water box.

13. In a device of the class described, the combination of a conduit having a casing rising therefrom, a front sheet arranged vertically in said casing and having an opening at the bottom through which liquid may flow along the conduit, a vertically movable water box in said casing, means for 10 yieldingly supporting said water box, said box having a hole in the bottom, a headgate fastened to the box in position to move vertically in a plane parallel and adjacent to and behind said front sheet, said gate having an off-center opening near the bottom for admitting water to the water box, and creating a whirl or circular movement of the water in the box.

14. In combination, a conduit having a 20 cylindrical casing rising therefrom, a transverse front sheet arranged vertically in said casing, a slight distance behind the foremost point of the casing, thereby forming a well at the front of the casing, the front sheet

terminating short of the bottom of the conduit whereby water may flow past the front sheet, and a headgate movably mounted behind said front sheet, said headgate being yieldingly suspended and provided with a water box, the headgate having an opening 30 leading into the box for admitting water to the box from the well.

15. In combination, a stationary casing having a vertical front sheet, a vertically movable water box behind the front sheet, 35 said box having a receiving opening in the side and two vertical channels at opposite sides, means confined at one point to the center of the box for suspending it, and rollers mounted on said casing, the planes of said 40 rollers pointing obliquely inward toward each other and toward said channels for holding the box in its proper position when moving vertically.

In witness whereof, I have hereunto sub- 45 scribed my name.

KARL F. KEELER.
